(Cl. D58—12)

To all whom it may concern:

Be it known that we, Henry E. Musselman and William H. Buck, citizens of the United States, residing at the city and county of Kalamazoo, State of Michigan, respectively, have invented a new, original, and ornamental Design for a Token Dispenser, of which the following is a specification, reference being had to the accompanying drawing, forming part thereof, in which:

Fig. 1 is a front perspective view, and
Fig. 2 is a rear perspective view of a token dispenser, showing our new design.

We claim:

The ornamental design for a token dispenser, as shown.

HENRY E. MUSSELMAN.
WILLIAM H. BUCK.
